[57] **ABSTRACT**

A stereophonic sound-reproducing system comprising two sound-reproducing sets separated by a base distance and each having a high-frequency section and a mid frequency section. The mid frequency section is provided with an acoustic focuser, the acoustic axis of which is so oriented towards the base line as to make the perception of the spatial sound panorama practically independent of the listener's position on a line parallel to the base line.

STEREOPHONIC SOUND-REPRODUCING SYSTEM

The present invention relates to radio engineering and, more specifically, to stereophonic sound-reproducing systems.

Stereophonic sound-reproducing systems usually consist of two sound-reproducing sets spaced some distance (referred to as a base) apart.

The acoustic axes of the reproducing sets are set at 60° to 90° to the base line. Each of the sets usually comprises high-frequency, centre-frequency and low-frequency sections. The stereophonic effect provided by said sound reproducing sets is felt only when the listener is at an equal distance from each set, i.e., on the axis of symmetry.

Even a slight deviation of the listener from the axis of symmetry distorts the sound panorama, as perceived by him, and most of the sound sources are picked up from the nearest sound reproducing set. If the listener is opposite one of the reproducing set, practically all the sound sources are picked up from that set. As a result, a sense of spatial sound panorama disappears and the perception is practically the same as monophonic. Thus, the zone, where the listener can freely move without an appreciable loss of the stereophonic effect, is restricted to a narrow strip along the symmetry axis of the sound-reproducing sets.

Known in the art is a stereophonic sound-reproducing system, in which the stereophonic effect zone is expanded by using sophisticated large-sized reflecting devices, comprising more than two parabolic reflectors for different sections of the frequency range.

Also known in the art is a stereophonic sound-reproducing system comprising more than two sound-reproducing sets. As the listener leaves the stereophonic effect zone of the main pair of sound-reproducing sets, he enters the stereophonic effect zone of another pair of sets. A system comprising, for instance, four sound-reproducing sets takes much space in the room, for the sets are not set in a line while the increase in the four set stereophonic system, as compared to the conventional stereophonic systems, makes the system much costlier.

Also known in the art is a stereophonic sound-reproducing system, wherein the stereophonic effect zone is increased by providing the walls of the audition room with special corrugated screens. As a result, the listeners pick up the sounds reflected from the corrugated screens. Thus the sounds, coming directly from the sets, are artificially attenuated, which brings about a drop in localization precision.

Owing to their complexity and large dimensions the above stereophonic sound-reproducing systems are usually ill-suited for individual use.

Known in the art is a stereophonic sound-reproducing system, wherein an increase of the stereophonic effect zone is understood as the improvement of one of the components of the stereophony and which provides a constant overall loudness of both sound-reproducing sets in a considerable part of the audition room. At the same time no allowance is made for the effect of the time difference $\Delta\tau_{xy}$ depending on the coordinates (x, y) of the listener's position. The effect of the time difference $\Delta\tau_{xy}$ largely determines the distortion of the spatial sound panorama.

An object of the present invention is to provide a system which avoids the aforesaid disadvantages.

The main object of the invention is to produce a stereophonic sound-reproducing system which will considerably expand the stereophonic effect zone while eliminating the distortions of the spatial sound panorama.

This object is accomplished by providing the midfrequency section of the stereophonic sound-reproducing system with an acoustic focuser whose acoustic axis is so oriented with respect to the base line as to make the perception of the spatial sound panorama practically independent of the listener's position on a line, parallel to the base line.

One of the embodiments of the invention may be realized with an acoustic focuser designed as a laminar acoustic lens the plates of which are set at 40° relative to a 2.4-m long base line.

Another embodiment of the invention consists in having the acoustic axis of the high-frequency section oriented at approximately the same angle to the base line as that of the mid-frequency section.

A system, realized according to the present invention, with only two sound-reproducing sets makes it possible to expand the stereophonic effect zone practically to 90 percent of the space in the audition room space.

The invention will now be explained in terms of supportive theoretical data and described by way of example with reference to the accompanying drawings, in which:

FIG. 1 is a top plan view showing left- and right-hand mid-frequency sections provided with a laminar acoustic lens:

FIG. 2 is a graphical illustration showing optimum directivity patterns of the mid-frequency (right- and left-hand) sections; and

FIG. 3 is a schematic diagram which illustrates the stereophonic effect zone where *a* is the stereophonic effect zone of existing systems and *b* is a stereophonic effect zone of the present system.

As is known, the various constituents of a stereophonic effect, i.e. sound "transparency," "acoustic atmosphere" and localization ensuring the subjective possibility of perception of spatially separated sound sources are closely interrelated. A violation of the relative arrangement of the various components of the stereophonic panorama with the listener in an asymmetric position (so-called spatial distortions) have an adverse effect on other aspects of stereophonic perception, too. Moreover, an additional type of distortion appears — violations of the musical balance — which finds its expression in an exaggerated loudness of the sound sources located in the set, nearest to the listener. Therefore, the existing stereophonic sound-reproducing systems lose the advantages of stereophony to a large extent when the listener is in an asymmetric position relative to the sound-reproducing sets.

The causes of spatial distortions are: the time difference $\Delta\tau_{xy}$, determined by the listener's co-ordinates

$$\Delta\tau_{xy} = 1_1 - 1_2/v;$$

the intensity difference

$$\Delta L_{xy} = 20 \lg 1_1/1_2;$$

the directivity factor difference

$$20 \ln D_1(\psi) - 20 \ln D_2(\psi)$$

different spectra of the signals, received from the sound-reproducing sets at the listening point, determined by the frequency dependence of the directivity patterns of the sound reproducing set section, wherein: l_1 and l_2 are the distances from the listening point to the sound reproducing sets, V is the velocity of sound velocity, and $D_1(\psi)$ and $D_2(\psi)$ are the directivity patterns of the left- and right-hand mid-frequency sections, respectively.

In the existing stereophonic sound-reproducing systems all the above factors contribute to a still greater displacement of the apparent sources in the direction of the listener's displacement, the time difference $\Delta\tau_{xy}$ exercising the greatest effect.

It is known that the time ($\Delta\tau_{xy}$) and intensity (ΔL_{xy}) differences between two channel signals exercise an equivalent and mutually independent effect on binaural hearing. In other words, the overall displacement of the apparent source

$$S(\Delta L_{xy}, \Delta\tau_{xy}) = S(\Delta L_{xy}) + S(\Delta\tau_{xy}) \quad \Delta\tau_{xy} = 0 \quad \Delta L_{xy} = 0$$

The intensity difference, equivalent in effect to the time difference, equals

$$\Delta L_{xy} \text{ eq} = k \cdot \Delta\tau_{xy}$$

where k is the equivalence coefficient in $\text{db}/\text{m} \cdot \text{sec}$ dependent on the co-ordinates of the listening point.

Then, the overall intensity difference with due regard to the equivalent will equal

$$\Delta L_{xy} \text{ total} = \Delta L_{xy} + k \cdot \Delta\tau_{xy}$$

Thus, an increase of the delayed signal level may offset the effect of the time difference $\Delta\tau_{xy}$ on the aural sense of direction. This may be accomplished with the aid of certain directivity patterns of the sound-reproducing set sections.

The optimum directivity patterns of the sections may be derived from the condition that the position of one of the apparent sound sources, e.g., the central one, remains unchanged as the listener moves parallel to the base line.

This condition may be roughly expressed by the following equation

$$\Delta L_{xy} + k \cdot \Delta\tau_{xy} + 20 \ln D_1(\psi) - 20 \ln D_2(\psi) = 0$$

The optimum directivity patterns, rated for different bases and presented in FIG. 2, illustrate the parts of the directivity patterns which correspond to the direction towards the listener's positions. For other directions (for $\psi > 60^\circ$) the shape of the directivity patterns may be arbitrary from the standpoint of the stabilization of the spatial sound panorama. It is, however, desirable that the values of the directivity factors for these directions be as small as possible.

The directivity of an individual mid-frequency section is much lower than the optimal value. Therefore, an acoustic focuser is required in the mid-frequency range. The required directivity of the mid-frequency section in a horizontal plane is ensured by using, for example, a laminar acoustic lens the design of which depends on the length of the base line selected.

The present stereophonic sound-reproducing system comprises two base-separated sound-reproducing sets, each of which comprises three sections, placed one above another, for the high, middle and low frequencies, respectively. Each section is supplied via separat-

ing filters. The overall width of the frequency range, reproduced by the present system, is determined by the selection of high- and low-frequency speakers.

The mid-frequency sections 1 (FIG. 1) comprising 5 two speakers 2 each, are supplied with a laminar acoustic lens 3. With base B 2.4 m long, the acoustic lens 3 has between six and eight parallel plates 4, set at an angle of 40° relative to the base line and diminishing in length in a direction outwardly along the base line. The 10 laminar acoustic lenses 3 impart to the mid-frequency sections 1 certain directivity patterns $D_1(\psi)$ and $D_2(\psi)$, shaped on the basis of studying the characteristics of man's aural analyzer. Optimum directivity patterns 5, 6 and 7 for the left-hand mid-frequency section and 8, 9, 10 for the right-hand mid-frequency section are estimated depending on different base lengths and illustrated in FIG. 2.

The difference in directivity factors enables the listener at an arbitrary point A in the audition room to 20 pick up the signals from the distant mid-frequency section at a higher level than from the nearer section. The magnitude and sign of this difference are calculated to compensate for the effect on the hearing organ of the time difference and the intensity difference due to the 25 difference in the distances l_1 and l_2 from the point A to the mid-frequency sections. As a result, the position of each of the apparent sound sources in the stereophonic panorama is practically independent of the listener's position.

It should be also noted that the required directivity 30 at high frequencies between 3 and 5 kHz may be provided by the orientation of the acoustic axis of the high-frequency section, shown in dotted outline by numeral 35 11 in FIG. 1 at roughly the same angle as that of the mid-frequency section. At the same time it is desirable to reduce excessive directivity in the higher-frequency range (over 5 kHz).

FIG. 3 illustrates the boundaries of the stereophonic 40 effect zone within which the spatial distortions do not exceed 10 percent, where a -is the stereophonic effect zone of the existing systems and b -is the stereophonic effect zone of the present system. This means that the 45 central apparent source of the perceived spatial sound panorama is displaced by not more than ± 0.18 . As may be seen from FIG. 3, the present system makes it possible to expand the stereophonic effect zone up to 90 percent of the audition room space.

The present system was tested and produced favorable 50 results. A series of comparative auditions of the herein proposed and existing stereophonic systems was made, and as a result, the following was established:

1. The present system produced a stable stereophonic panorama for listeners both on the axis of symmetry of the sound-reproducing sets and away from it.

2. The sound quality of this system is preferred by the 55 vast majority of listeners who are off the symmetry axis of the sound reproducing sets and is estimated as equivalent to the existing stereophonic sound-reproducing 60 systems when positioned on the axis of symmetry. The advantages of the present system are displayed particularly in reproducing stereophonic programs with a complex spatial panorama (e.g., symphonic music) as well as at listening points opposite one of the sound reproducing sets (left- or right-hand).

3. The loudness ratio of the various elements of the stereophonic panorama (the musical balance) remains

practically unchanged within a considerable part of the room.

4. For this system there is no appreciable difference between the perception of stereophonic sound on the symmetry axis of the sound reproducing sets and aside from it.

What is claimed is:

1. A stereophonic-sound reproducing system comprising: two sound-reproducing units symmetrically positioned on a base line and separated by a base distance, each unit having a mid-frequency section and a high-frequency section, and acoustic focussing means positioned in front of said mid-frequency section, each mid-frequency section having an acoustic axis inclined with respect to the base line, the acoustic axes of both mid-frequency sections facing inwardly in converging fashion and intersecting on an axis of symmetry of the units, each acoustic focussing means comprising a plurality of spaced vertical plates extending parallel to the

acoustic axis of the respective mid-frequency section, said plates having a length in a horizontal plane which decreases with increased distance of the plates from said axis of symmetry, whereby to make the perception of the spatial sound panorama produced by said units practically independent of the listener's position on a line parallel to the base line.

2. A stereophonic sound-reproducing system as claimed in claim 1, wherein said plates are disposed at an angle of 40° relative to said base line, the latter being 2.4 m long.

3. A stereophonic sound-reproducing system as claimed in claim 1, wherein each said high-frequency section is oriented relative to the base line so that the acoustic axis of said high-frequency section is at approximately the same angle to the base line as that of the associated mid-frequency section.
